UNITED STATES PATENT OFFICE.

ALFRED THRUSTON POPE, OF LOUISVILLE, KENTUCKY, ASSIGNOR OF ONE-HALF TO
CURRAN POPE, OF LOUISVILLE, KENTUCKY.

EGG-TURNING MECHANISM FOR INCUBATORS.

1,254,273.

Specification of Letters Patent. Patented Jan. 22, 1918.

Application filed April 27, 1917. Serial No. 165,025.

To all whom it may concern:

Be it known that I, ALFRED THRUSTON POPE, a citizen of the United States, residing at Louisville, county of Jefferson, and State 5 of Kentucky, have invented certain new and useful Improvements in Egg-Turning Mechanism for Incubators; and I do hereby declare the following to be a full, clear, and exact description of the invention, such as 10 will enable others skilled in the art to which it appertains to make and use the same.

This invention relates to incubators, and more particularly to the egg turning mechanism thereof.

15 It is well known in the art that during the period of incubation, the eggs should be turned at predetermined intervals, in order that the best results may be obtained.

Furthermore, it is desirable to turn the 20 drawers of the incubator end for end, and in incubators where more than one drawer is used, it is desirable to interchange the drawers. In this manner, all of the eggs are subjected to the same conditions during the 25 period of incubation, and, consequently, the greatest production is obtained.

It is an object of my invention to provide 30 means for rolling or turning the eggs, which means is so constructed that it will permit the withdrawal and reversal of the drawers and also the interchanging of the same, and so that it will properly coöperate with the egg rolling frame of any one of the drawers.

It is a further object of my invention to 35 so construct the aforementioned means that all of the eggs in all of the drawers of a sectional incubator may be simultaneously turned or rolled by a single manual operation, and it is a still further object to so 40 construct the actuating means that it may be rendered operative or inoperative by a single manual operation.

Furthermore, I contemplate constructing 45 the device in such manner that it may be incorporated in many commercial machines which are at present in use with only slight modifications of the same, and may be, of course, built into new machines.

With these and other objects in view, 50 such as will appear as my description progresses, my invention comprises the combination and arrangements of parts as set forth in and falling within the scope of the appended claims.

In the drawings:

55

Figure 1 is a sectional view from front to rear of a sectional incubator with my invention incorporated therein;

Fig. 2 is a fragmental end elevation;

Fig. 3 is a fragmental front sectional view 60 showing portions of two incubator sections taken along the broken line 3—3 in Fig. 1;

Fig. 4 is a section on line 4—4 of Fig. 1, illustrating the manner of connecting the two sections of the actuating shaft together; 65

Fig. 5 is a plan view of an egg drawer showing the egg rolling or turning frame therein;

Fig. 6 is a fragmental perspective of an 70 egg drawer showing the elongated opening *per se*;

Fig. 7 is a perspective of the connection between the shaft sections; and

Fig. 8 is a detail of the crank locking means.

75

In the drawings, I have illustrated a sectional incubator, two sections 1 and 2 being disclosed, which sections are placed side by side on a suitable support, in the usual manner, with the adjacent walls 3 and 4 abutting. Each of the sections is divided into a plurality of compartments 5 and 6 for the reception of the egg drawers. These egg drawers 7 are located in the compartments in spaced relation to the bottom, are supported, removably, by cleats 8, and are adapted to be removed from the sections through doors 9. The drawers are preferably rectangular and slide on the cleats into and out of position, the proper positioning 85 being obtained by the contact of the drawers with a suitable stop, such as the back of the incubator. The bottom of each egg drawer is made of wire mesh and is provided with an elongated opening 10 at the central portion thereof.

An egg rolling or turning frame 11 is mounted within each of the egg drawers for reciprocation, the rolling frame being shorter than the egg drawer. This egg rolling frame is provided with transversely extending bars 12, between which the eggs are adapted to be located and which are such distances apart that the eggs will rest on the bottom of the drawer. Thus when the egg 100 rolling frames are moved in one direction or the other, the eggs will be turned.

In order that the eggs in all of the

drawers of a sectional incubator may be turned, I have provided the following mechanism. Extending longitudinally through the incubator, at right angles to the line of reciprocation of the egg rolling frames, is a sectional shaft 13, which is mounted in suitable bearings 14, and one end of which extends through the side wall of the end-most section. On one end of one section of the rod is secured, by means of a set screw 15, a fork-shaped member 16, between the legs of which, a crank 17 operates, the crank being properly secured to the adjacent end of the next section by a set screw 18. Thus when the first section is turned, the rotary motion will be imparted to all of the sections of the shaft. The shaft is made in sections in this manner to facilitate the setting up and operation of the incubator, for it has been found in actual practice that the incubator sections vary in construction to such an extent that it would be impossible to have the sections of the shaft 13 in perfect alinement, and, consequently, it would be impracticable to positively couple the ends of the sections of the shaft together. Located on the shaft 13, adjacent to each of the egg drawers, is an eccentric, which is designated generally by the reference character 19, and which comprises a casting having a cam portion 20 and a flange 21 thereon, which casting is secured to the shaft by a set screw 22. It comprises further a second casting 23, which forms the flange 24 corresponding to the flange 21 and is secured to the shaft by a set screw 25. Surrounding the cam portion 20 of the eccentric is a cam strap 26, which is formed on the end of a connecting rod 27. The placing of the strap on the cam 20 is greatly facilitated by the making of the eccentric in two pieces, as the strap may be slipped upon the cam before the casting 23 is moved into place. Each of the connecting rods 27 is provided with an upwardly extended portion 28 which is adapted to project into a socket 29 formed in a bar 30 on each of the egg rolling frames, but is so constructed that it may be freely disengaged from said socket, so that the connecting rod may drop below the bottom of the adjacent egg drawer to permit the removal of the latter. Thus the connecting rods will not only have a reciprocatory movement produced by the action of the eccentric, but may also have a pivotal movement, so that they may be swung to and from engagement with the sockets 29.

In order that the connecting rods may be simultaneously raised or lowered to engage or disengage in the sockets 29, I have provided a second shaft 31 which is, like the shaft 13, formed in sections, and which sections are connected together by cranks 32 and forked connecting members 33, the shaft 65 being mounted in suitable bearings 34. On

this shaft 31 is a plurality of cams 35, which cams are arranged beneath the connecting rods 27, so that the latter rest upon the same. The cams are provided with side flanges 36, which prevent the accidental disengagement 70 of the connecting rods. With this construction, it will be seen that the connecting rods may be raised to their operative positions, where they will engage in the sockets 29, or may be lowered and disengaged from the 75 sockets upon the proper rotation of the shaft 31, and the consequent movement of the cams 35. It is, of course, to be understood that when the vertical portions of the connecting rods swing upwardly into the sockets 80 29, they pass through the elongated openings 10 in the bottoms of the egg drawers, so that they will be free to reciprocate the egg rolling frames without imparting movement to the egg drawers themselves. 85

Mounted on the end of the shaft 13, which protrudes beyond the end of the incubator, is a worm wheel 37, which meshes with a worm 38 carried by a rod 39, which rod is mounted in suitable bearings 40 on the end 90 of the incubator and is provided with a crank handle 41, by means of which it may be operated. Thus, when the crank handle 41 is turned, motion will be imparted to the shaft 13 through the worm 38 and the worm 95 wheel 37, and the connecting rods will cause the reciprocation of the egg rolling frames, so that the eggs will be properly turned. The crank handle, of course, may be turned in either direction to impart the proper 100 movement to the egg rolling frames and the extent of movement may be gaged by an indicator which is formed on the face of the worm wheel 37.

The shaft 31 is rotated by means of a 105 crank handle 42 which is secured to the end of the shaft which protrudes through the end of the incubator and which crank may be secured in either one of two positions by means of a pin 43, which passes through the 110 crank and into apertures 44 in the adjacent end of the incubator. Thus, when the cam 35 is in its raised position, the crank will be in the position illustrated in Fig. 2, but when the cam is in its lowered position, the 115 crank will occupy an opposite position, and the pin 43 will extend through the lower aperture 44.

From the foregoing description, it will be seen that I have so constructed the actuating means for the egg turning frames that but a single manual operation will be necessary to accomplish the reciprocation of all of the frames, and I have further so connected the actuating means to the egg turning frames that they may be readily disengaged therefrom to permit the withdrawal of the drawers, the reversal or the interchanging of the same. Furthermore, I have so constructed the means for rendering the 130

actuating means operative or inoperative that it, too, may be actuated by a single manual operation.

What I claim is:—

5 1. In an incubator, the combination with an egg drawer, of an egg rolling frame adapted to reciprocate therein, and pivotally mounted, reciprocating means detachably engaged with the frame for actuating 10 the same, whereby the drawer may be removed and turned end for end during the period of incubation.

15 2. In a sectional incubator having longitudinally disposed sections, the combination with a plurality of egg drawers arranged in said sections adapted to be removed and turned end for end, of egg rolling frames adapted to reciprocate therein, means adapted to engage with each frame 20 irrespective of its position for reciprocating the same, and means common to all of said last-mentioned means for actuating the same.

25 3. In a sectional incubator, the combination with a plurality of egg drawers adapted to be removed and turned end for end, of egg rolling frames adapted to reciprocate therein, means adapted to engage with each frame for reciprocating the same, common 30 means for rendering the reciprocating means operative or inoperative, and common means for actuating the reciprocating means.

35 4. In an incubator, the combination with an egg drawer adapted to be removed and turned end for end, of an egg rolling frame adapted to reciprocate therein, means for reciprocating the frame irrespective of its position including an oscillatory shaft, a 40 connecting rod having eccentric connection with the shaft and direct detachable connection with the frame, means for actuating the shaft, and means for establishing or destroying the connection between the rod and 45 frame.

50 5. In a sectional incubator, the combination with a plurality of egg drawers, of egg rolling frames mounted therein and adapted to reciprocate in the drawers, means to reciprocate the frame including a sectional shaft, a loose connection between the sections, a connecting rod for each frame having an eccentric connection with the shaft, and a detachable connection with the 55 frame, and means for oscillating the shaft.

55 6. In an incubator, the combination with an egg drawer, of an egg rolling frame adapted to reciprocate therein, and reciprocating means movable to engage and disengage the egg rolling frame, for actuating the latter, whereby the drawer may be removed and turned end for end during the period of incubation.

7. In an incubator, the combination with an egg drawer, of an egg rolling frame 65 adapted to reciprocate therein, an oscillatory and reciprocatory element, means for reciprocating said element to actuate the frame, and means to oscillate the element to engage it with and disengage it from the 70 frame.

8. In an incubator, the combination with an egg drawer, of an egg rolling frame adapted to reciprocate therein, means arranged beneath the drawer for detachably 75 engaging the frame to reciprocate the same, and means for actuating the last-mentioned means.

9. In an incubator, the combination with an egg drawer, of an egg rolling frame 80 adapted to reciprocate therein, means passing through the bottom of the drawer and detachably engaged with the frame for reciprocating the latter, and means for actuating the last-mentioned means. 85

10. In an incubator, the combination with an egg drawer, of an egg rolling frame adapted to reciprocate therein, means extending through the bottom of the drawer and detachably engaged with the frame for 90 reciprocating the same, means for controlling the engagement between the last-mentioned means and the frame, and means for actuating the frame-reciprocating means.

11. In an incubator, the combination with 95 an egg drawer, of an egg rolling frame adapted to reciprocate therein, an oscillatory and reciprocatory element arranged beneath the frame, means for raising and lowering the element into and out of engagement with the frame, and means for actuating the element to reciprocate the frame. 100

12. In a sectional incubator, the combination with a plurality of egg drawers arranged in substantially the same horizontal 105 plane, of egg rolling frames adapted to reciprocate therein, oscillatory and reciprocatory elements adapted to engage said frames, means common to all of said elements for imparting oscillatory movement 110 thereto to engage and disengage them with and from the said frame, and means common to all of said elements for imparting reciprocatory movement thereto to actuate the frames. 115

13. In an incubator, the combination with a removable egg drawer, of an egg rolling frame adapted to reciprocate therein, and reciprocating means, movable into and out of the path of movement of the drawer to 120 engage and disengage the egg rolling frame, for actuating the latter, whereby the drawer may be removed and turned end for end during the period of incubation.

In testimony whereof I affix my signature. 125
ALFRED THRUSTON POPE.
